Primary Examiner—Louis S. Zarfas*Assistant Examiner*—Monica A. Weingart*Attorney, Agent, or Firm*—Ostrager, Chong & Flaherty[57] CLAIM

The ornamental design for boxer shorts, as shown.

DESCRIPTION

FIG. 1 is a front elevational view of the boxer shorts design of the invention; and,

FIG. 2 is a rear elevational view thereof.

The broken line showing of a torso and upper legs is for illustrative purposes only and forms no part of the claimed design.
